Atlys.*

UNITED STATES PATENT OFFICE.

GEORGE C. FEDDERMAN, OF DETROIT, MICHIGAN, ASSIGNOR TO AUTO LOADING DEVICE MANUFACTURING COMPANY, OF DETROIT, MICHIGAN, A CORPORATION OF MICHIGAN.

NAIL.

Application filed February 4, 1926. Serial No. 85,942.

My invention is a nail adapted to be driven to a limited extent so that its head portion will be left protruding slightly so that the nail readily can be drawn from its position in the wood for reuse. Such a nail is desirable for use in connection with making temporary forms for concrete building when it is of advantage to use again the material making up the forms, it being possible to withdraw the nails without damage to the material, or such nails are useful in connection with returnable shipping material where it is desirable to knock down the forms or structures so that the material composing them can be used over again.

In the accompanying drawing

Figure 1 shows the nail in side view and Fig. 2 shows the nail in end view.

In these drawings 1 indicates the stem or body portion of the nail and 2 indicates an integral cylindrical enlargement forming a shoulder at 3 extending around the main or body part.

This enlargement merges into a flaring terminal formation 4 which forms the head proper, this being of larger diameter than the cylindrical shoulder portion. This flared head portion 4 is in the form of an inverted frustum of a cone, and is adapted to receive beneath it the claw of the extracting implement.

In driving the nail it will enter the wood or other material until the annular shoulder 3 rests thereon. This limits the degree to which the nail enters the material so that the inverted frusto-conical formation will be left standing out from the surface of the material together with the cylindrical enlargement forming the stop. This cylindrical stop portion is sufficiently long to locate the inverted frustum of a cone at proper distance from the surface of the wood or other

material to permit the ready introduction of the claw between the head and the material. Furthermore the rounded surfaces of the frustum of the cone and the cylindrical stop portion enables the claw to be quickly and readily placed as no square or flat surfaces are opposed to the thrust of the claw in positioning it for performing the withdrawal of the nail, but on the contrary the frusto-conical formation acts as a guide for directing the claw into place.

This nail is economical in manufacture which involves only a one blow operation, a minimum amount of stock is required. There is ample stock for receiving the claw, yet the head does not protrude so far as to be in the way or offer any substantial obstruction. There is no excessive amount of stock in the head and the nail can be coated economically. With the conically formed head herein described there is no liability of crystallization in manufacture as there is in the ordinary wire nail with a thin sharply flanged head.

Owing to the frusto-conical formation joined to the enlarged cylindrical stop portion, the head is strong and will stand the strain of driving or extracting without danger of rupture.

I claim:

A wire upset nail having a stem or body with a head integral therewith, said head having a shouldered portion of larger diameter than the stem, presenting at its junction with the stem a flat annular surface or shoulder, and an inverted frusto-conical portion adjoining the shouldered portion, the diameter of the shouldered portion being no greater than the smaller diameter of the conical portion.

In testimony whereof I affix my signature.
GEORGE C. FEDDERMAN.
